UNITED STATES PATENT OFFICE.

HERMAN A. PAQUETTE, OF FAIRMOUNT HEIGHTS, MARYLAND.

WRENCH.

SPECIFICATION forming part of Letters Patent No. 791,644, dated June 6, 1905.

Application filed October 13, 1904. Serial No. 228,254.

To all whom it may concern:

Be it known that I, HERMAN A. PAQUETTE, a citizen of the United States, residing at Fairmount Heights, in the county of Prince George and State of Maryland, have invented new and useful Improvements in Wrenches, of which the following is a specification.

My invention relates to wrenches of the adjustable class; and its object is to provide a wrench which will combine stability and strength and simplicity with perfect and instantaneous adjustability.

Another object of my invention is to provide a wrench which may be easily and rapidly adjusted to nuts of different sizes and conformation without the necessity of manipulating screws or employing other cumbersome means rendering the adjustment of the wrench awkward and difficult.

A further object of my invention is to provide a device of the character about to be described which may be accurately adjusted to the contour of any nut and readily operated with one hand upon any number of nuts of various sizes in succession within the limits of its dimensions.

It is furthermore purposed with this invention to provide a wrench comprising but few and simple parts, each individually compact, strong, and durable, which parts may be easily and speedily assembled and which may be conveniently disassociated from each other for purposes of cleaning or for replacement of those parts which may have become worn by constant usage.

A further and great advantage of this wrench resides in the rigidity of the movable jaw, which is materially increased when in its adjusted position by the exertion of great force upon the wrench for tightening nuts.

With these and other objects in view my invention consists in the features, details of construction, and combination of parts hereinafter more specifically referred to and described, as are illustrated in the accompanying drawings, forming part of this specification, in which—

Figure 1 is a side view; Fig. 2, a longitudinal section; Fig. 3, a like view showing a slight modification; Fig. 4, a detail section of the operating means.

Like characters of reference denote like parts wherever they occur throughout the various views of the drawings.

Referring to the drawings, 1 is a shank or rack-bar having fixedly mounted thereon a jaw 2 and preferably made integral with one end of said shank or rack-bar for a more thorough coöperation with the movable jaw 3. This movable jaw comprises a frame having parallel arms 4 and 5 and a connecting-strip 6, the jaw and connecting-strips being provided with longitudinal apertures 7 of the size and rectangular shape and for the reception of the said shank or rack-bar 1. In order to permit of an oscillatory movement of said slidable jaw upon the shank or rack-bar, the diameter of the upper aperture in said movable jaw, while still preserving its rectangular conformation, is increased, this provision enabling the movable jaw to be rocked into and out of engagement with the shank or rack-bar 1 and admitting of the vertical movement of said jaw along the shank or rack-bar in order to adapt the distance between the movable and the stationary jaw to the nut to be adjusted to the wrench. The inner wall of said aperture is provided with teeth milled to tightly and firmly engage with the shank or rack-bar 1.

Upon the arm 5 of the movable jaw is a shoulder 8, cast or otherwise formed, inclining toward the shank or rack-bar, said shoulder serving to receive a wedge or other suitable means for firmly clamping the movable jaw in its adjusted position. In the present instance this wedging means consists of a roller 9, Figs. 2 and 4, rotatively mounted within a flanged yoke 10, Fig. 1, and operable between the shoulder and shank or rack-bar 1. The flanges on said yoke serve to guide the roller 9 in its upward and downward path. A rod 11, extending through an aperture provided for this purpose in the connecting-strip 6, protrudes

into the yoke and is there securely fastened in any suitable manner, preferably, however, for facilitating the removal of the separate parts by a nut 12, screwed to the extremity 5 of the shank of said rod, said nut snugly fitting the space formed by the walls of the yoke. Intermediate the yoke and connecting-strip is a spring 13, bearing against the yoke and strip and adapted to automatically lock said afore- 10 mentioned movable jaw in its position of adjustment. On the end of the rod is a thumb-piece 14, having a recess which conforms to the shape of the shank or rack-bar, along which it intended to travel, and by the inser- 15 tion of the thumb or other member between the movable jaw and thumb-piece it will be evident that this action will release the lock and at the same time rock the jaw.

In order to insure a smooth and even travel 20 of the movable jaw along the rack-bar, a re- sili ent spring 16 is placed between the shank and the walls of the movable jaw, the tend- 25 ency of this spring being to force said mov- able jaw away from the rack and normally hold it disengaged from the rack while the movable jaw is in its upward and downward travel.

In Figs. 2 and 4 the means operating to se- 30 cure the movable jaw to the rack-bar consists of a roller traveling along an inclined shoul- der. It is to be understood that a wedge or any other means for accomplishing this pur- 35 pose falls within the scope of this invention. In Fig. 3 a wedge 15 is shown operating to 40 perform the same function as that of the roller, and while this invention is not restricted to the use of a roller or wedge the views embodying these means have been represented to show the most advantageous manner of

construction of my invention.

From the above specification and construc- 45 tion as represented in the accompanying drawings it will be plainly seen that by press- ing or pulling on the thumb-piece 14 the mov- able jaw may be operated in either direction necessary to adjust the wrench to any size of nuts.

What I claim, and desire to secure by Let- 50 ters Patent of the United States, is—

50 1. In a wrench, the combination, with a sta- tionary jaw and a rack-bar, of a movable jaw on said rack-bar, said movable jaw comprising a frame provided with openings through which extends the rack-bar, and having adja- 55 cent said rack-bar an inclined face, a spring- pressed rod slid able within said frame, a yoke carrying a roller adapted to travel along the incline and fastened to the rod, and a thumb- piece for operating the rod.

60 2. In a wrench, the combination, with a sta- tionary jaw and a rack-bar, of a movable jaw

on said rack-bar, said movable jaw comprising a frame provided with openings through which extends the rack-bar, and having adja- 65 cent said rack-bar an inclined face, a spring- pressed rod slid able within said frame, a yoke carrying a roller adapted to travel along the incline and fastened to the rod, and a thumb- piece for operating the rod.

3. A wrench having a fixed jaw and a shank, a rocking jaw co-operating therewith having an inclined way, a spring-actuated locking- 70 roller between the way and the shank, and a headed shaft for operating such device, the head of the shaft being so proportioned with respect to the rear of the rocking jaw that 75 the entry of the thumb or other member between them will both release the lock and rock the jaw, as set forth.

4. A wrench comprising a stationary jaw, a shank, a movable jaw having an inclined way, an operating-rod mounted between the way and the shank and carrying a roller, a spring coiled around said operating-rod to normally hold the roller against the inclined way and shank for locking the movable jaw 90 against said shank, substantially as described.

5. In a wrench, the combination with a sta- tionary jaw and a toothed shank, of a rock- 95 ing movable jaw having an inclined way and teeth for engaging the teeth of the shank, a roller mounted between the shank and inclined way, said roller having end flanges fitting each side of the shank, a spring to nor- mally hold the roller against the inclined way and shank for locking the movable jaw against 100 said shank, and a spring for normally holding said teeth out of engagement with the shank, substantially as described.

6. A wrench comprising a stationary jaw, a shank, a movable jaw mounted on the shank and having an extension spaced from the shank and inclined on its face adjacent the shank, a roller mounted between the shank and the extension, flanges on said roller bearing on each side of the shank, a shaft extend- 105 ing from the roller and mounted in an aperture in the extension, a spring interposed be- 110 tween the roller and the extension, said spring normally forcing the intermediate part of the roller into engagement with the incline and the shank for locking the movable jaw against the shank, substantially as described.

7. A wrench comprising a stationary jaw, a shank having teeth on one edge, a movable jaw mounted on the shank and having teeth 115 formed on the inside thereof and an exten- 120 sion spaced from the shank and inclined on

its face adjacent the shank, a roller mounted between the shank and the extension, flanges on said roller bearing on each side of said shank, a shaft extending from the roller and 5 mounted in an aperture in the extension, a spring interposed between the roller and the extension and normally forcing the intermediate part of the roller into engagement with the incline and the shank and causing the

teeth to interlock and lock the movable jaw 10 on the shank, substantially as described.

In testimony whereof I affix my signature in presence of two subscribing witnesses.

HERMAN A. PAQUETTE.
